United States Patent Office

Des. 216,108
Patented Nov. 25, 1969

216,108

RESIDENTIAL BUILDING

Arthur Carol Sanford, 2308 Bay Drive, Hillsboro Shores,
Pompano Beach, Fla. 33062

Filed Apr. 29, 1969, Ser. No. 16,943

Term of patent 14 years

Int. Cl. D25—04

U.S. Cl. D13—1

FIG. 1

FIG. 2

FIG. 3

FIG. 4

FIG. 1 is a perspective view of a residential building embodying my new design.

FIG. 2 is a front end elevation thereof.

FIG. 3 is a plan elevation thereof.

FIG. 4 is a side elevation thereof, showing the front end on the left, the opposite being the opposite hand and otherwise identical.

I claim:

The ornamental design for a residential building, as shown and described.
